United States Patent Office

Des. 190,232
Patented May 2, 1961

190,232

DATA TRANSMITTER

Frank Wilkey, Jr., Johnson City, N.Y., assignor to International Business Machines Corporation, New York, N.Y., a corporation of New York

Filed July 5, 1960, Ser. No. 61,203

Term of patent 14 years

(Cl. D26—5)

FIG. 1

FIG. 2

FIG. 3

FIG. 4

Fig. 1 is a front perspective view of a data transmitter showing my new design.

Fig. 2 is a rear perspective view of the same.

Fig. 3 is a top plan view of the same.

Fig. 4 is a front elevational view of the same.

The essential features of my new design are shown in solid lines in the drawings.

I claim:

The ornamental design for a data transmitter, as shown and described.
